Primary Examiner — Derrick Holland(74) *Attorney, Agent, or Firm* — Studebaker & Brackett PC(57) **CLAIM**

The ornamental design for a motor for railway vehicle, as shown and described.

DESCRIPTION

FIG. 1 is a front perspective view of the front, right, and top sides of a motor for railway vehicle showing our new design; FIG. 2 is a rear perspective view of the rear, left, and bottom sides;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown represent unclaimed subject matter of the motor for railway vehicle and form no part of the claimed design.
